RETAINING-VALVE ANCHOR

Application filed June 4, 1928. Serial No. 282,726.

Our invention relates to means whereby the retaining valves of the air lines of a railroad car may be properly anchored or secured to the end walls of railroad cars; said means involving a construction which permits of vertical adjustment to be made in the event of replacement or renewal of the vertical portion of the air line or pipe; while at the same time permitting adjustments to compensate for any possible variations that may occur in the relation between the bolt-holes in the laterally disposed lug of the retaining valve.

The invention contemplates means whereby the retaining valve will be firmly secured to the wall of the car, while at the same time permitting adjustment and detachment of the valve without necessitating removal of the supporting means or anchor and therefore without necessitating entering into the car which, at frequent times, would require the lading of the car to be removed.

The objects and advantages of our invention will be readily comprehended from the detailed description of the accompanying drawing, wherein—

Figure 1 is a front elevation of a retaining valve attached to our improved retaining valve anchor which is shown attached to a portion of a car wall and with a portion of the air pipe secured to the valve.

Figure 2 is a side elevation of the structure disclosed in Figure 1, with a portion of the car wall shown in section.

Figure 3 is a perspective view of our improved retaining valve anchor.

In the exemplification of the invention as disclosed in the accompanying drawing, 10 indicates a portion of a car wall, usually the end wall adjacent to which a portion of the air line or pipe is vertically disposed; a portion of the pipe being shown at 11.

Attached to the upper end of the vertical pipe 11 is the usual well known type of retaining valve 12. These valves are generally provided with laterally disposed lobes or ears 13, 13 provided with bolt-holes for the reception of suitable bolts whereby the retaining valve is fastened in place. As the valve is of well known construction and forms no part

of our invention, a detailed description thereof need not be entered into.

Our improved means involves a suitable plate 14, preferably rectangular as shown in Figure 3, provided at a suitable point with a number of bolt or rivet-receiving holes, as at 15, 15. In the particular exemplification, the plate 14 is shown riveted at 16 to the car wall 10, although it is obvious that where the car wall is of wood construction, suitable bolts may be employed if desired instead of rivets.

The lateral width of the plate 14 is preferably somewhat greater than the distance between the ends of the lobes 13, 13 of the retaining valve; and the plate at points commensurate with the usual distance between the centers of the bolt-holes in the lobes or ears 13, 13 is provided with a pair of projections or pins 17, 17 arranged parallel with each other and extending outwardly from the rectangularly formed base portions 18. The opposite sides of the base portions 18 are each provided with a pivot-providing pin or projection 19, see Figure 2. The pins 19 are offset from the center or median line of the pins 17 and are formed integral with or secured to the base portions 18 so as to be immovable so far as the portions 18 are concerned; while the outer ends of said pins 19 are preferably flared or provided with the head portions 20 which are countersunk in the rear face of the plate 14. The plate 14 is provided with openings through which the pins 19 are disposed, with the head portions 20 of the pins so arranged that tight frictional relation with the plate 14 will be provided and the too free rotary movement of the pins 19 in the plate 14 prevented.

At the same time the securement of the pins 19 in the plate 14 is such that rotation of the pins 19 by the use of sufficient force through the application of a suitable tool or wrench to the squared or angularly faced portion 18 is possible and the portions 18 moved about the axes of the pins 19, 19.

It is apparent from the construction shown that by causing the composite valve holding pins 17—18—19 to be moved about their axes, the centers of the pins 17, 17 may be moved

either upwardly or downwardly or farther apart or brought closer together, because of the off-set or eccentric relation between pins 17 and the pins or portions 19.

5 With this construction, it is evident that in the event replacement of the retaining valve is necessary and a variation in the distance between the bolt-holes of the new retaining valve is encountered, our improved 10 anchoring means may be easily adjusted to compensate for such variation by simply rotating the anchoring means about the axes of the pins 19, 19 to a sufficient extent thereby causing the valve-lug receiving portions 15 or pins 17, 17 to be moved farther apart or brought closer together, as the case may be; such movement being due to the eccentric relation of the pins 19, 19 to the pins 17, 17.

It is thus clearly apparent that our improved anchor is readily adaptable to retaining valves wherein the distance between the centers of the holes in the valve-lugs may slightly vary.

The pins or projections 17, 17 are of length 25 sufficient to extend through the valve-lugs and are preferably threaded as shown at 21, to receive suitable nuts 22, after the valve is in place, for the purpose of firmly holding the retaining valve in place on the anchor.

30 The valve receiving projections or pins preferably are shown with the squared or angular portions or bases 18, which permit a wrench to be readily applied when it is found necessary to adjust the relation between the pins 17, 17; the bases 18 at the same time maintaining proper spaced relation between the valve 12 and the plate 14.

It is evident that the degree of adjustment is controlled by the extent to which the portions 19, 19 are off-set from the axial centers 40 of the portions or pins 17, 17; and that the manner of construction of said pins and their attachment to the base plate 14 may be altered without, however, departing from the spirit of our invention.

45 In the event of vertical adjustment being necessary by reason of variation in length of the air pipe, such adjustment may be had by rotating the pins so as to cause pins 17, 17 to be disposed above or below the axial centers of the pins 19, 19.

What we claim is:

1. A retaining valve anchor comprising a supporting plate adapted to be secured to a 55 car wall, said plate being provided with valve receiving projections disposed outwardly in parallel relation and rotatably secured to the plate with the valve receiving ends of the projections off-set from the axes of the rotatably secured portions to permit vertical adjustment and to compensate for variations in the valve bolt-hole relations.

60 2. A retaining valve anchor comprising a supporting plate adapted to be secured to a car wall, said plate being provided with a

pair of valve receiving pins off-set intermediate of their ends, with one end of each pin rotatably secured in the supporting plate.

3. A retaining valve anchor comprising a supporting plate adapted to be secured to a car wall, said plate being provided with valve-engaging means rotatably secured thereto, with said secured portions of the means off-set from the longitudinal axes of the valve receiving portions to permit vertical adjustment of the valve receiving portions and to accommodate varying bolt-hole relations upon rotative movement of said means, said means having wrench receiving and valve spacing portions.

4. A retaining valve anchor comprising a supporting plate adapted to be secured to a car wall, and a pair of valve-lug engaging pins extending outwardly from and rotatably secured to said plate, said pins being off-set 85 intermediate of their ends to permit the outer ends of said pins to move in circles about the inner attached ends, said pins adjacent to the inner ends being provided with wrench engaging surfaces.

5. A retaining valve anchor comprising a supporting plate adapted to be secured to a car-wall, valve-lug engaging pins provided with heads at their inner ends adjacent to said plate, and means whereby said heads are rotatably secured to said plate, said pins and said means having eccentric relation.

6. A retaining valve anchor comprising a supporting plate adapted to be secured to a car-wall, and valve engaging means rotatably secured to said plate with the plate engaging ends off-set from the longitudinal axes of the valve-engaging ends.

GEORGE HEIDMAN.
VICTOR H. HARBERT.
